Inventor, Robert M. Fryer

United States Patent Office.

ROBERT M. FRYER, OF NEW YORK, N. Y., ASSIGNOR TO UNIVERSAL PUMP AND MANUFACTURING COMPANY.

Letters Patent No. 78,816, dated January 14, 1868.

IMPROVEMENT IN PUMPS.

The Schedule referred to in these Letters Patent and making part of the same.

TO ALL WHOM IT MAY CONCERN:

Be it known that I, ROBERT M. FRYER, of the city, county, and State of New York, have invented certain Improvements in Pumps; and I do hereby declare that the following is a full and exact description thereof, which will enable others skilled in the art to make and use the same, reference being had to the accompanying drawings, representing, in—

Figure 1, a transversal section of my improved pump, through the line $x x'$, and in

Figure 2 a longitudinal section of the same, through the line $z z'$.

This invention has for its object to obtain a pump, which, by being free from the objections of a pump blowing off air with its water, will furnish a steady and solid stream of water; and my attention has also been directed toward producing a pump not affected by the gravel or any sediment which may be sucked up by the receiving-valve.

The peculiar construction of the pump, and the arrangement of its various parts, are as follows: A is the cylinder of the pump, provided with a piston, B, worked by the rod C. The cylinder A is bolted to the upright chambers D D', in which the cylinder penetrates, so as to leave all around an annular channel, $\alpha \alpha$. The lower part of the chambers D D' is prolonged downwards, and enlarged to any extent necessary to form sediment-receivers E E', which are proportionate in size to the purity or impurity of the water or liquid to be worked by, and in the pump. The hand-holes $e e$ are for cleaning out the receivers E E'. The upper part of the chamber D is composed of an upright cylinder, P, having on one side, and at its upper part, the inlet or receiving-valve chamber and valve S, and on the other side, and at its lower part, the delivery-valve chamber and valve T.

In double-acting pumps, I connect these valves by pass-pipes, and place thereon air-receivers, in the ordinary manner. The top, U, of the chamber P is conical, and it is surmounted by a small chamber, F, packed with pieces of sponge, to form what I call my porous diaphragm. K is a valve-box, in which there is a small valve, opening upward, as a delivery-valve. L is the pipe, leading from the valve-box K to the air-separating reservoir M. S'' and S''' are small cocks, one at top the other at bottom of the reservoir M, by means of which the liquid accumulating in the reservoir M can be drawn off, and the air can be expelled by the top cock S'' as fast as it accumulates.

The advantages of my improved pump are easily appreciated if we examine its mode of working, as it is evident that if any air is admitted by the receiving-valve in the valve-box S', it will, as represented by f in fig. 2, rise at once to the top of the chamber P, in the space U, to be forced out through the porous diaphragm in the chamber F, the valve of the valve-box K, and pipe L, when the pressure is applied to that end of the pump. When any gravel or other impurities are also admitted by the valve-chamber S', it will gravitate, as indicated by the letters $\alpha \alpha \alpha$, in the fig. 1, and be collected in the reservoir E. When the piston is reversed, and that pressure exerted on this side of the pump, the air is expelled, as already stated, and the water alone will pass out through the delivery-valve chamber T, for the opening into that chamber is too low to admit of any air escaping through it, and too high for any sediment to be ejected through it, so that a perfect solid stream of water will be the result.

The small amount of liquid expelled from the pump by the valve in the valve-box K, when the pump is not "working air," is collected in the reservoir M, from whence it may be discharged by the cock S'', to be saved or wasted, as the case may be.

The pump may be made double-acting, such as I have represented it in my drawings, or it can be made single-acting, and in that case one of the chambers D D' would be dispensed with, and the reservoir M, if used, might be placed in any other place more appropriate to the designs of the pump.

I claim as my invention, and desire to secure by Letters Patent of the United States—

1. The vertical chambers D D', having sediment-chambers E E', vertical cylindrical chambers P P', with conical tops U U', and diaphragm-chambers F F', in combination with a horizontal cylinder, A, arranged as described, and operating in the manner set forth.

2. The arrangement of the valve-chambers S', T, and K, in their relative positions one to the other, to operate substantially as specified.

3. The diaphragm-chamber F, in combination with the valve-chambers K, S, and T, substantially as described.

ROBERT M. FRYER. [L. S.]
